GLASS TUBE FLOWMETER

Harold W. Metzger, Warminster, Pa., assignor to
Fischer & Porter Company, Warminster, Pa.

Filed Oct. 6, 1970, Ser. No. 25,351

Term of patent 14 years

Int. Cl. D10—08

U.S. Cl. D52—6

FIG. 1 is a front perspective view of my design for a glass tube flowmeter;

FIG. 2 is a rear perspective view of the flowmeter;

FIG. 3 is a side view of the flowmeter;

FIG. 4 is an end view of the flowmeter; and

FIG. 5 is a perspective view of the glass tube element shown separately for clarity of illustration.

I claim:

The ornamental design for a glass tube flowmeter, substantially as shown and described.
